(57) **CLAIM**

The ornamental design for an infusion device, as shown and described.

DESCRIPTION

FIG. 1 is a perspective view of an infusion device showing our new design, with a cover shown in a secured position; FIG. 2 is a top view of the infusion device shown in FIG. 1; FIG. 3 is a left side elevational view of the infusion device shown in FIG. 1;

FIG. 4 is a front elevational view of the infusion device shown in FIG. 1;

FIG. 5 is a rear elevational view of the infusion device shown in FIG. 1;

FIG. 6 is a right side elevational view of the infusion device shown in FIG. 1; and,

FIG. 7 is a bottom view of the infusion device shown in FIG. 1.

The broken line showing of two rounded features in FIG. 7 is for the purpose of illustrating portions of the article and forms no part of the claim.

1 Claim, 4 Drawing Sheets
